CLAIM

The ornamental design for a night vision scope, as shown and described.

DESCRIPTION

FIG. 1 is a perspective view of a night vision scope, showing my new design;

FIG. 2 is an another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the night vision scope that form no part of the claimed design.
